HAT BRIM

Alfons Uriwal, Laredo, Tex., assignor to Texas
Harvest Hat Company, Inc., Laredo, Tex.

Application August 24, 1934, Serial No. 741,188

9 Claims. (CL 2—178)

This invention relates to new and useful improvements in straw hats and relates to improvements in my patent application entitled Straw helmet hat, filed September 6, 1933, Serial No. 5 688,342.

It has been discovered that the constructions of the brims of straw hats with radial corrugations or ridges extending to the edges of the brims are defective in several respects. First, the edges 10 of brims in which the radial corrugations extend to the edges are very thick without corresponding rigidity. Second, the extension of the corrugations to the very edges serves to render the edges soft in that the ends of the corrugations 15 have very little strength when compressed. Third, the application of bindings upon the edges of the brims is unsatisfactory due to the necessary thickness, and the mounting of them in position is exceptionally difficult.

20 This invention has for an object the construction of the brims of straw hats with radial corrugations or ridges in such a manner that the various defects pointed out in the previous paragraph are eliminated.

25 More particularly, the invention proposes to construct corrugations or ridges which do not extend completely to the edges of a brim. It has been found that the brim will be reinforced and stiffened because of the fact that the corrugations 30 terminate slightly before the edge. Furthermore, binding may be pleasantly and conveniently applied.

Another one of the objects of this invention is the application of binding strips in a particular 35 manner upon the edge of the brim so as to add to its reinforcement.

Still further, the invention contemplates to teach the manufacture of the brims of hats in a manner so that the cross sectional shape of the 40 corrugations or ridges are not limited to semi-circular but may be triangular, square, or of other shape.

Another one of the objects of this invention is an arrangement of bindings upon the brims of 45 straw hats in such a manner that portions thereof are detachable as desired to change or control the flexibility of the brims of the hats.

Still further, the invention proposes the construction of an article of the class described 50 which is simple and durable and which can be manufactured and sold at a reasonable cost.

For further comprehension of the invention and of the objects and advantages thereof reference 55 will be had to the following description and accompanying drawing and to the appended claims in which the various novel features of the invention are more particularly set forth.

In the accompanying drawing forming a material part of this disclosure:

Fig. 1 is a side elevational view of a straw helmet hat constructed according to this invention.

Fig. 2 is a fragmentary bottom elevational view of the brim of the hat shown in Fig. 1 seen as though looking in the direction of the line 2—2 of Fig. 1.

Fig. 3 is a fragmentary sectional view taken on the line 3—3 of Fig. 1.

Fig. 4 is another fragmentary sectional view but taken on the line 4—4 of Fig. 1.

Fig. 5 is a fragmentary sectional view of the brim of a straw hat constructed according to another embodiment of the invention.

Fig. 6 is another fragmentary sectional view of the brim of a straw hat constructed according to another modification of the invention.

Fig. 7 is a fragmentary bottom view of Fig. 6 looking in the direction of the line 7—7 of Fig. 6.

Fig. 8 is a perspective view of a portion of the binding used in Figs. 6 and 7.

Fig. 9 is a sectional view taken on the line 9—9 of Fig. 8.

Fig. 10 is a side elevational view of a plain straw hat embodying this invention.

Fig. 11 is an elevational view of a fedora shaped straw hat embodying this invention.

Fig. 12 is a fragmentary sectional view of a portion of a brim of a straw hat illustrating another embodiment of the corrugations or ridges.

In Figs. 1—4 inclusive, a helmet type straw hat 10 is illustrated with a brim 10a. This brim is shown formed with a plurality of upward radial corrugations 11 having their ends blending into the material of the brim. More particularly, the corrugations or ridges 11 extend from points 11a 35 slightly spaced from the inner diameter of the brim to points 11b slightly spaced from the free edge of the brim. These corrugations are of semi-circular shape in transverse cross section.

The edge of the brim 10a is finished with a binding strip 12 sewed thereon. This binding strip may be narrow or wide depending merely upon taste. The outer ends of the corrugations or ridges 11 should extend just up to the edge of the binding strip 12 to obtain the best results. 45 Thus, if the binding strip is narrow the corrugations or ridges are slightly further extended and if wide are slightly less extended.

It is a feature of this invention that the free edge of the brim is not corrugated but plain. It 50 is a further feature of this invention that the corrugations or ridges extend just to a small distance from the free edge so that the brim is reinforced by the rigidity of the corrugations and the free edge is reinforced also because of the 55 close proximity of the corrugations, but at the same time the free edge is thin.

In Fig. 5 another embodiment of the invention is disclosed which distinguishes from the previous form in the provision of a double binding. There 60

is an interior binding 12 and an exterior binding 12a engaged thereover. The exterior binding is of larger size so that there is a relative taper of the edge of the binding towards the material of the brim. The double binding serves to further reinforce and stiffen the edge of the brim of the hat.

In Figs. 6-9 inclusive, another embodiment of the invention has been disclosed in which the 10 brim 10a of the hat 10' is provided with radial corrugations or ridges 11 terminating slightly from the edges thereof. A reinforcement strip 14 of cardboard or fiber material is engaged upon the free edge of the brim. This reinforcement strip has its outer edge 14a turned over so as to engage over the edge of the brim. Small radial members 15 project from the strip 14 and are adapted to engage within the hollow undersides of the outer ends of the corrugations or 20 ridges 11.

These projecting members are similarly shaped as the hollows of the corrugations. They are detachably mounted in position by reason of being formed with tongues 16 upon their outer ends 25 engaging receiving grooves upon the edge of the strip 14, and furthermore, because of the provision of prongs 17 stamped from the material of the members and engaging into the material of the ridges or corrugations 11. The arrangement 30 is such that the rigidity produced by the corrugations or ridges 11 are directly communicated by the members 15 to the edge of the brim of the hat. If it is desired to eliminate this direct communication then the members 15 may be removed 35 by forcing the prongs 17 free from the material of the corrugations 11 and then moving the members 15 to disengage the tongues 16. A binding strip 12b is engaged over the turned edge of the strip and is secured in position with 40 stitches 20. These stitches 20 also engage through material of the strip 14 which is soft enough to permit this construction.

In Fig. 10 another embodiment of the invention is disclosed wherein the conventional shape straw hat 10b is shown formed with a brim 10a constructed according to this invention. Similar parts may be recognized by the same reference numerals.

In Fig. 11 the invention is shown applied to a 50 fedora shaped straw hat 10c. The straw hat is provided with a brim 10a constructed according to this invention.

In Fig. 12 a corrugation or ridge 11d is shown 55 distinguishing from the previous illustrated ridges 11 by the fact that it is of triangular or pointed shape. This form is illustrated merely to call attention to the fact that the cross sectional shape of the corrugations or ridges may be varied.

60 While I have illustrated and described the preferred embodiments of my invention, it is to be understood that I do not limit myself to the precise constructions herein disclosed and the right is reserved to all changes and modifications 65 coming within the scope of the invention as defined in the appended claims.

Having thus described my invention, what I claim as new and desire to secure by United States Letters Patent is:—

70 1. In a hat, a brim of inverted cup shape formed with a plurality of upwardly embossed radial corrugations or ridges having ends blend-

ing into the material of the brim near the inner and outer edges thereof and forming a rigid brim with thin edges.

2. In a hat, a brim of inverted cup shape 5 formed with a plurality of upwardly embossed radial corrugations or ridges having ends blending into the material of the brim near the inner and outer edges thereof and forming a rigid brim with thin edges, said corrugations or ridges being of semicircular cross sectional shape.

10 3. In a hat, a brim of inverted cup shape formed with a plurality of upwardly embossed radial corrugations or ridges having ends blending into the material of the brim near the inner and outer edges thereof and forming a rigid brim 15 with thin edges, and binding material attached upon the free edge of said brim, the outer ends of said corrugations or ridges terminating at the inner edges of the binding.

4. In a hat, a brim of inverted cup shape 20 formed with a plurality of upwardly embossed radial corrugations or ridges having ends blending into the material of the brim near the inner and outer edges thereof and forming a rigid brim 25 with thin edges, and a binding for the free edge of the brim including a reinforcement strip with an edge bent around the edge of the brim, and provided with radial members engaging the undersides of the corrugations.

30 5. In a hat, a brim of inverted cup shape, 35 formed with a plurality of upwardly embossed radial corrugations or ridges having ends blending into the material of the brim near the inner and outer edges thereof and forming a rigid brim with thin edges, and a binding for the free edge 35 of the brim including a reinforcement strip with an edge bent around the edge of the brim, and provided with radial members engaging the undersides of said corrugations, said radial members being detachably mounted in position.

40 6. In a hat, a brim of inverted cup shape formed with a plurality of upwardly embossed radial corrugations or ridges having ends blending into the material of the brim near the inner and outer edges thereof and forming a rigid brim 45 with thin edges, and a binding for the free edge of the brim including a reinforcement strip with an edge bent around the edge of the brim, and provided with radial members engaging the undersides of said corrugations, said radial members being detachably mounted in position, with 50 interengaging tongues and prongs.

7. In a hat, a brim formed with a plurality of upwardly embossed radial corrugations or ridges having ends blending into the material of the brim near 55 the inner and outer edges thereof and forming a rigid brim with thin edges.

8. In a hat, a brim formed with a plurality of embossed radial corrugations or ridges having ends blending into the material of the brim near 60 the inner and outer edges thereof and forming a rigid brim with thin edges.

9. In a hat, a brim formed with a plurality of embossed radial corrugations or ridges having ends blending into the material of the brim near 65 the outer edges thereof and forming a rigid brim with thin edges, and binding material mounted upon the edge of said brim and having elements reinforcing said corrugations or ridges.

70 ALFONS URIWAL.
